UNITED STATES PATENT OFFICE.

STEPHEN M. GREEN AND WILLIAM T. McFARLAND, OF NEW YORK, N. Y.

PIPE-BENDER.

No. 806,085.

Specification of Letters Patent.

Patented Nov. 28, 1905.

Application filed April 22, 1905. Serial No. 256,921.

To all whom it may concern:

Be it known that we, STEPHEN M. GREEN and WILLIAM T. McFARLAND, citizens of the United States, and residents of the city of New York, borough of Brooklyn, in the county of Kings and State of New York, have invented a new and Improved Pipe-Bender, of which the following is a full, clear, and exact description.

10 This invention relates to improvements in tools for bending pipe, the object being to provide a tool of this character having its head so shaped as to adapt the tool for bending pipe of different sizes without danger of 15 kinking or flattening the same.

Other objects of the invention will appear in the general description.

We will describe a pipe-bender embodying our invention and then point out the novel 20 features in the appended claims.

Reference is to be had to the accompanying drawings, forming a part of this specification, in which similar characters of reference will 25 indicate corresponding parts in both the figures.

Figure 1 is a plan of a pipe-bender embodying our invention and showing the same as engaging with a length of pipe, and Fig. 2 is a section on the line xx of Fig. 1.

30 The head of the tool comprises walls 1, 2, which are divergent, thus giving a substantially **V** shape to the work-engaging surface of the head, and thus providing for engaging the head with the different sizes of pipe. The

35 base of the head or the junction of the two walls is longitudinally curved, as indicated by dotted lines 3 in Fig. 1, and this curve 3 terminates in abrupt curved portions 4, which will permit of a slight freedom of the pipe

40 as it is bent, therefore obviating any danger of breaking the pipe. Coacting with the head is a hook-shaped jaw 5, the three members of said jaw being extended one from another at substantially right angles, so that opposing

45 corners are provided permitting the jaw to engage with different sizes of pipe. The hook portion 5 has a movement in a slot 6, formed in the wall 1 of the head, and it also has a threaded stem 7, which passes into the tubular

50 shank 8, extended from the head, and engaging with this threaded stem 7 is a nut 9 for adjusting the jaw. This nut 9 projects through opposite openings in the shank 8 and has its periphery milled, as clearly indicated in Fig. 2.

55 We have shown a handle or lever 10 as de-

tachably connected to the shank 8 of the head; but it is obvious that the shank may be continued to form the handle or lever. It will be noted that the hook-shaped jaw 5 is comparatively narrow and is arranged between 60 the ends of the head walls.

In the operation a straight pipe or a pipe to be bent is passed between the free end of the hook-jaw 5 and the wall 2 of the head, which is somewhat shorter than the wall 1 of 65 said head, and then the hook-jaw is to be adjusted sufficiently tight against the pipe.

By swinging the lever in the direction of the length of the pipe the bend will be formed to any desired degree over the head. 70

Having thus described our invention, we claim as new and desire to secure by Letters Patent—

1. A pipe-bender comprising a head having a longitudinally-curved and transversely **V**-shaped work-engaging surface, and a hook-jaw coacting with said head. 75

2. A pipe-bender comprising a head having a longitudinally-curved and transversely **V**-shaped work-engaging surface, the ends of 80 the curve being somewhat abrupt with relation to the main portion thereof, and an adjustable hook-shaped jaw coacting with the head.

3. A pipe-bender comprising a head, longitudinally curved on its work-engaging side and having divergent walls, a tubular shank extended from the head and having lateral openings, a hook-shaped jaw having a threaded stem passing into the tubular shank, and an 90 adjusting-nut engaging with said stem and extending outward through said lateral openings. 85

4. A pipe-bender comprising a head having divergent walls, the said head being longitudinally curved at the base or junction of said 95 walls, one of said walls being slotted, a tubular shank extended from the head, a hook-shaped clamp adapted to move in said slot of said wall, a threaded stem extended from the clamp into the tubular shank, and an adjusting-nut engaging with the said stem. 100

In testimony whereof we have signed our names to this specification in the presence of two subscribing witnesses.

STEPHEN M. GREEN,
WILLIAM T. McFARLAND.
